(57) **CLAIM**

The ornamental design for a memory interface for rearview assembly as shown and described.

DESCRIPTION

FIG. 1 is a bottom front perspective view of a memory interface for a rearview assembly of the present disclosure; FIG. 2 is a bottom rear perspective view of the memory interface of FIG. 1;

FIG. 3 is a rear elevational view of the memory interface of FIG. 1;

FIG. 4 is a left side elevational view of the memory interface of FIG. 1;

FIG. 5 is a right side elevational view of the memory interface of FIG. 1; and

FIG. 6 is a bottom plan view of the memory interface of FIG. 1;

FIG. 7 is an enlarged bottom front perspective view of the memory interface of FIG. 1;

FIG. 8 is an enlarged bottom plan view of the memory interface of FIG. 6; and,

FIG. 9 is an enlarged bottom rear perspective view of the memory interface of FIG. 2.

Broken lines are environmental only and form no part of the claimed design.

1 Claim, 9 Drawing Sheets
